UNITED STATES PATENT OFFICE.

SAMUEL PEMBERTON AND JOHN F. DEADMAN, OF SAULT STE. MARIE,
MICHIGAN.

MARINE BOAT.

No. 811,171.

Specification of Letters Patent.

Patented Jan. 30, 1906.

Application filed July 18, 1905. Serial No. 270,213.

To all whom it may concern:

Be it known that we, SAMUEL PEMBERTON and JOHN F. DEADMAN, citizens of the United States, residing at Sault Ste. Marie, in the 5 county of Chippewa and State of Michigan, have invented certain new and useful Improvements in Marine Boats, of which the following is a specification.

This invention relates to a boat of the type 10 comprising an outer shell provided with an exterior propeller and mounted to rotate about an inner shell which is equipped with living quarters and with the engines and other appurtenances for safety, comfort, and 15 the management of the boat.

For a full description of the invention and the merits thereof and also to acquire a knowledge of the details of construction of the means for effecting the result reference is 20 to be had to the following description and accompanying drawings.

While the invention may be adapted to different forms and conditions by changes in the structure and minor details without de- 25 parting from the spirit or essential features thereof, still the preferred embodiment is shown in the accompanying drawings, in which—

Figure 1 is a side view of a boat embodying 30 the invention. Fig. 2 is a central longitudinal section of the inner hull or shell. Fig. 3 is a detail view illustrating the hollow rudder-post and its adjoining parts. Fig. 4 is a detail view of the rudder. Fig. 5 is a vertical central longitudinal section of the outer hull, 35 showing the inner hull or shell in full.

Corresponding and like parts are referred to in the following description and indicated in all the views of the drawings by the same 40 reference characters.

The boat comprises an inner shell or hull 1 and an outer shell or hull 2, the latter being rotatable about a longitudinal axis and provided upon its exterior with a spiral propeller 3, which may consist of a continuous 45 wind or of a series of paddles or blades.

A hollow shaft 4 extends centrally of the boat, projects beyond the extremities thereof, and is made conical at its ends, so as to offer a 50 minimum amount of resistance to the propulsion of the boat. The hull or shell 1 is connected to the shaft 4 in any substantial manner, the two parts—the hull 1 and the shaft 4—being relatively fixed, whereas the shell or

hull 2 is rotatable, antifriction-bearings being provided between contracted ends of the hull 2 and the end portions of the shaft adjacent to the extremities of the hull 1. The joints are made tight, so as to obviate leaking, which would necessitate the expenditure of force for expelling bilge-water. The cabins and other quarters provided for the occupants of the boat are suitably distributed throughout the length and at the sides thereof. The engines 5 for propelling the boat are located so as to distribute the weight uniformly of the boat, as well as to secure an equalization of the strain incident to propulsion when the boat is in motion. It is to be observed that the engines and other weighted adjunctive parts occupy the lowermost position, this being of advantage in order to have the metacenter at as low a point as possible, whereby the stability of the boat is assured. Any well-known type of gearing may be resorted to for transmitting power to the outer shell or hull for rotation thereof. It is preferred to provide a series of toothed rings at intervals in the length of the hull 2 and have the same intermesh with pinions connected with the respective engines to be driven thereby.

A pilot-house 6 is located at each end of the boat and is mounted upon the terminal extensions of the shaft 4. A vertically-disposed tubular bearing 7 is arranged near each end of the shaft 4 and receives the hollow post 8 of a rudder, said post 8 being provided at its lower end with a valve constituting a sea-cock, whereby water may be pumped in the boat when required for any purpose. The specific arrangement to accomplish this end is best seen by reference to Fig. 3. The tubular bearing 7 is mounted on the outer end of the shaft 4 and receives the hollow rudder-post 8, which is provided at its lower end with a ball cock or valve 8^a. The hollow rudder-post 8 is provided inside of the tubular extension 7, which forms a bearing therefor, with suitable ports 8^b, through which water pumped into the hollow rudder-post may find egress into the tubular bearing 7 and thence into a water-pipe 8^c, mounted inside of the shaft 4 and provided with any suitable form of valve 8^d. The smoke-stack 105 for carrying off the smoke and products of combustion from the furnaces of the several engines passes through the shaft 4 and out-

ward and upward, as shown at 9, to discharge the smoke at a convenient point.

The outer shell or hull 2 is provided with hatches 10, by means of which egress and ingress to the boat is had. Folding hooks 11 are disposed at intervals in the length and circumference of the outer hull for securing the boat when moored. The hooks 11 are adapted to fold into pockets or depressions formed in the outer side of the hull 2, so as to be out of the way when the boat is in motion.

Having thus described the invention, what is claimed as new is—

1. A boat of the character described comprising a longitudinal shaft, two concentric hulls, one of which is fast on said shaft and the other of which rotates outside of the fixed hull, the outer hull being provided with a propeller, a pilot-house at each end of the said shaft outside of the said hulls, and a hollow rudder-post secured in the end of the shaft and provided with an opening to admit of

water being pumped therethrough for the purpose set forth.

2. A boat of the character described comprising a longitudinal shaft, an inner hull fixed on said shaft, and an outer concentric hull designed to rotate on the shaft and provided with a propeller, hollow tubular bearings 7 secured to the shaft at each end thereof outside of said outer hull, pilot-houses supported at the end of said shaft, and a rudder having a tubular post mounted in the tubular bearings 7 and arranged to admit of water being pumped through the post for the purpose set forth.

In testimony whereof we affix our signatures in presence of two witnesses.

SAMUEL PEMBERTON. [L. s.]
JOHN F. DEADMAN. [L. s.]
